UNITED STATES PATENT OFFICE.

EMIL SALTZKORN AND LUDWIG NICOLAI, OF DRESDEN, GERMANY.

DESIGN FOR A BOX-STRIP.

SPECIFICATION forming part of Design No. 25,580, dated June 2, 1896.

Application filed April 25, 1896. Serial No. 589,124. Term of patent 7 years.

To all whom it may concern:

Be it known that we, EMIL SALTZKORN and LUDWIG NICOLAI, citizens of Germany, residing at the city of Dresden, Germany, have 5 invented a new and original Design for Box-Strips, of which the following is a full, clear, and exact description.

The nature of our design is fully illustrated in the accompanying drawings, in which—
10 Figure 1 is a perspective view of one face of a portion of the strip, and Fig. 2 is a similar view of the same.

As illustrated in the drawings, the strip is thin and comparatively narrow, while on each 15 edge are a series of equidistant semicircular projecting portions *b*, arranged as shown, the edge of the strip connecting them in a continuous series. On one face, immediately in the center of each semicircular portion *b*,

is a cluster of pointed projections *c*, arranged 20 in a circular line, as shown, while on the opposite face, as shown in Fig. 2, immediately in the center of the semicircular projections are a series of openings *d*.

Having thus described our invention, what 25 we claim, and desire to secure by Letters Patent, is—

The design for a box-strip substantially as described and as illustrated in the accompanying drawings. 30

In witness whereof we have hereunto set our hands this 19th day of March, A. D. 1896.

EMIL SALTZKORN.
LUDWIG NICOLAI.
